UNITED STATES PATENT OFFICE.

JESSE NEWMAN, OF ATLANTA, ILLINOIS.

IMPROVEMENT IN FIRE-KINDLERS.

Specification forming part of Letters Patent No. **149,510**, dated April 7, 1874; application filed
March 14, 1874.

To all whom it may concern:

Be it known that I, JESSE NEWMAN, of Atlanta, in the county of Logan and State of Illinois, have invented a new and valuable Improvement in Fire-Kindlers; and I do hereby declare that the following is a full, clear, and exact description of the construction and operation of the same, reference being had to the annexed drawings making a part of this specification, and to the letters and figures of reference marked thereon.

Figure 1 of the drawing is a representation of an outside view of my fire-kindler. Fig. 2 is a sectional view of the same, and Fig. 3 is a view of the extinguisher.

My invention has relation to fire-kindlers, which consist of a metallic perforated case secured on a rod or handle, and containing some refractory absorbing substance which will hold in its pores a flammable fluid.

The improvement which I have made on these devices consists in making the case tapering or conical, and combining therewith a metallic extinguisher or shield, as I will now proceed to explain.

In the annexed drawings, A designates a conical shell or case containing any suitable porous substance, B, which is refractory, such, for instance, as burned clay, asbestos, and the like. The case A is thickly perforated, and the holes may be opposite holes or recesses *a* made into said porous substance for the purpose of readily saturating this substance with a flammable fluid, and obtaining a large flame

when the kindler is ignited. D designates a rod or handle of suitable length, which passes longitudinally and centrally through the kindler, and is firmly secured to it by means of nuts, which are screwed up tightly against removable heads *b b*. By taking off the end nut the kindler can be detached from its handle, and the substance B removed from it. C designates a cone-shaped shield or extinguisher, which is constructed to fit tightly over the kindler, and which is intended for extinguishing the flame on the kindler after a fire is properly lighted, and also for preventing evaporation of the flammable fluid left in the kindler.

By constructing the case A of a conical form it is more readily and conveniently used than are the cylindrical kindlers, and by so constructing the kindler I am able to employ the extinguisher to advantage.

What I claim as new, and desire to secure by Letters Patent, is—

The combination of the extinguisher or shield C, the perforated conical case A, containing a porous refractory substance, B, and secured on a handle, as herein set forth, and for the purpose explained.

In testimony that I claim the above I have hereunto subscribed my name in the presence of two witnesses.

JESSE NEWMAN.
